UNITED STATES PATENT OFFICE.

CHARLES M. TIPTON, OF RAPIDAN, VIRGINIA.

NUT AND BOLT LOCK.

SPECIFICATION forming part of Letters Patent No. 657,256, dated September 4, 1900.

Application filed February 2, 1900. Serial No. 3,743. (No model.)

To all whom it may concern:

Be it known that I, CHARLES M. TIPTON, a citizen of the United States, residing at Rapidan, in the county of Culpeper and State of Virginia, have invented certain new and useful Improvements in Nut and Bolt Locks; and I do hereby declare the following to be a full, clear, and exact description of the invention, such as will enable others skilled in the art to which it appertains to make and use the same.

This invention relates to nut and bolt locks, and in common with this class of devices aims to secure the nut and the bolt against relative casual displacement after the nut has been turned up tight against the object to be secured or fastened.

The improvement consists, primarily, of a nut having a transverse key-seat intersecting with the bolt-opening and a key to interlock with the bolt and key-seat of the nut and having a cleft-terminal, which is spread or oppositely deflected when driving the key home, so as to prevent its accidental displacement, the nut having at the remote end of the key-seat a spreader in position to engage with the cleft-terminal of the key and effect a spreading of the cleft members, so as to effect the desired result.

The improvement also consists in having the receiving end of the key-seat of the nut of wedge form or similar construction to interlock positively with the key and in having the opposite or remote end of the key-seat formed with divergent openings or passages separated by the spreader, which is located medially of the key-seat, so as to register with the cleft in the penetrating end portion of the key.

The improvement further consists of a key having its entrance end cleft, said cleft being flared to direct the spreader into the cleft when driving the key home, said key having its opposite end of approximately wedge form and provided with an offstanding portion to receive the blows of a hammer or like tool when it is required to remove the key.

For a full description of the invention and the merits thereof, and also to acquire a knowledge of the details of construction of the means for effecting the result, reference is to

be had to the following description and the drawings hereto attached.

While the essential and characteristic features of the invention are necessarily susceptible of modification, still the preferred embodiment of the invention is illustrated in the accompanying drawings, in which—

Figure 1 is a perspective view showing the application of the invention. Fig. 2 is a section at a right angle to the axis of the bolt. Fig. 3 is a side elevation looking toward the end of the key having the wedge-shaped portion. Fig. 4 is a detail perspective view of the key. Fig. 5 is a detail perspective view of the end portion of the bolt.

Corresponding and like parts are referred to in the following description and are indicated in all the views of the drawings by the same reference characters.

The bolt 1 and nut 2 may be of any pattern, size, or make, according to the desired location and character of work. A groove or seat 3 is formed in the end of the bolt 1 and extends transversely thereof and may be of any required depth. The nut 2 is provided with a transverse key-seat 4 in position to register with the groove or key-seat of the bolt. The key 5 is fitted into the seats 3 and 4 when in coincident relation and after the nut 2 has been turned up tight upon the bolt. In the event of the bolt being loose when the nut has received the final turn it will be necessary to interpose one or more washers of required thickness between the nut and the object to be secured, and the requisite thickness of washer will be determined by trial.

The groove or key-seat 4 intersects with the bolt-opening of the nut 2 and opens through the outer face of the nut at one end and is made of wedge form or otherwise constructed at said end to make positive interlocking connection with the key when the latter has been properly positioned. The opposite end portion of the key-seat 4 terminates in divergent openings or passages 6, separated by a cross-piece 7, which constitutes a spreader, the opposite side of said cross-piece or spreader being beveled to an edge, which faces toward the seat 4, so as to enter the cleft at the penetrating or entrance end of the key 5.

The key 5 has an end portion cleft, as shown at 8, and the outer end of the cleft is flared, as shown at 9, to admit of the spreader 7 readily entering the cleft 8 when driving 5 the key 5 home. This cleft end 8 is reduced and is located at the terminal of the key which is first introduced into the seat 4 and which is designated as the "entrance" or "penetrating" end. The opposite end of the key is 10 of wedge form, as shown as 10, to interlock with the corresponding end of the seat 4 and is also provided with an offstanding portion 11 to receive the blows of a hammer or other instrument when it is required to dislodge 15 the key 5, so as to admit of the loosening of the nut when the bolt is required to be removed.

The nut and bolt are used in the well-known manner, it being necessary to have the seats 20 3 and 4 register after the nut has received the final turn in order to make provision for the proper seating for the key 5, which is thrust into the registering seats until the cleft end 8 reaches the spreader 7, when the key 25 is struck one or more smart blows in order to cause the portions adjacent to the cleft to be oppositely deflected and hold the key in place against accidental slipping.

It is to be understood that one or more 30 washers (not shown) are to be interposed between the nut and the object to be fastened in the event of a space existing between said parts after the nut has been screwed home to the proper position.

Having thus described the invention, what 35 is claimed as new, and desired to be secured by Letters Patent, is—

1. In a nut and bolt lock, a nut having a transverse key-seat intersecting with the bolt- 40 opening and provided at one end with a spreader, and a key adapted to be fitted into said seat and having a terminal portion cleft and constructed to be spread by engagement with the said spreader when driving the key 45 home, substantially as set forth.

2. In a nut and bolt lock, a nut, having a transversely-disposed key-seat intersecting with the bolt-opening and having an end portion terminating in divergent passages, and 50 a key having a terminal portion cleft, said

key being adapted to be forced into the key-seat and to have the cleft portions spread by entering the divergent passages of the key-seat, substantially as set forth.

3. In a nut and bolt lock, a nut having a 55 transverse key-seat undercut at one end and divergent at the opposite end, a spreader at said divergent end of the key-seat, and a key having one end of approximately wedge form and its opposite end cleft and adapted to be 60 separated by engagement with the spreader, substantially as set forth.

4. In a nut and bolt lock, a nut having a transversely-disposed key-seat intersecting 65 with the bolt-opening, one end of the seat terminating in divergent passages and the opposite end being of approximately wedge form and opening through the outer face of the nut, and a key having a terminal portion cleft and having its opposite end portion of approximately wedge form and provided with an offstanding portion, substantially as set forth.

5. In a nut and bolt lock, a nut having a transversely-arranged key-seat intersecting 75 with the bolt-opening, and provided at one end with divergent passages and at its opposite end with a wedge-shaped portion, and a key having an end portion reduced and cleft, the outer end of the cleft being flared, and 80 having the opposite end of the key constructed of wedge form and provided with an off-standing portion, substantially as and for the purpose set forth.

6. In combination with a bolt having a 85 groove or seat in its threaded end, a nut having a transverse key-seat to register with the groove of the nut, one end of the seat being divergent and provided with a spreader, and a key adapted to be fitted into the registering 90 seats of the bolt and nut and having a cleft terminal portion, substantially as and for the purpose set forth.

In testimony whereof I affix my signature in presence of two witnesses.

CHARLES M. TIPTON. [L. S.]
